VERIFYING DEVICE

Clifford C. Leatherman, New York, N. Y., assignor
to Control Instrument Company, Inc., Brooklyn,
N. Y., a corporation of New York

Application May 20, 1948, Serial No. 28,085

4 Claims. (Cl. 73—156)

1

This invention relates to improvements in statistical card machines and has particular reference to a verifying device therefor.

As well known, verifying machines have been provided for checking the accuracy of data punched in a statistical card, wherein when an error has been made the sensing element or pin will contact the card and, in so doing, will prevent the operation of the escapement which would otherwise move the card to its next columnar position for verification.

Heretofore, in machines of this character, the inertia of the mass, which includes the punching key and its operating lever, is such that the striking of the key to depress the sensing pin causes the latter to engage the card, when no perforation is present, with such force that a permanent indentation is formed in the upper surface of the card and the lower surface thereof is embossed due to the coaction of the pin with the edge of the opening in the associated die plate, and it sometimes occurs, when the striking force exerted upon the key is excessive, that the pin will even penetrate the card, thus destroying its usefulness. The unavoidable embossing of the cards in the manner described has occasioned sufficient spacing of the cards when stacked in a magazine of a sorter, tabulator, or similar type of machine to, at times, cause the cards to be fed inaccurately from said magazine and beneath the usual throat plate and, so far as known, there has been no practical mechanical solution of the problem of eliminating these detrimental embossments.

It is therefore proposed, by the present invention, to overcome the above difficulties of either embossing or penetrating the cards by the provision of a simply constructed and effectively operable verifying device, which, upon contact of the sensing pin thereof with a card, will prevent the latter from becoming embossed at the point of contact of the pin therewith.

A further feature of the invention resides in the provision of means associated with the sensing pin of a verifying device which will, upon contact of said pin with a card, relieve the pin of any further pressure exerted on said device by its operating means.

The inventive idea involved is capable of receiving a variety of mechanical expressions one of which, for purposes of illustration, is shown in the accompanying drawing; but it is to be expressly understood that said drawing is utilized merely for the purpose of facilitating the description of the invention as a whole and not to define

2

the limits thereof, reference being had to the appended claims for this purpose.

In the drawings:

Fig. 1 is a fragmentary sectional view illustrating a verifying device constructed in accordance with the invention, and showing the operating means therefor;

Fig. 2 is an enlarged vertical section of the verifying device shown in Fig. 1, and taken on the line 2—2 of Fig. 3; and

Fig. 3 is a transverse section on the line 3—3 of Fig. 2.

For the purpose of showing one of many adaptations of the present invention, the same is illustrated in conjunction with an operating mechanism such as disclosed in the patent to Cleven, 2,102,577, dated December 14, 1937, only so much of said mechanism being shown as is necessary for a complete understanding of the instant device.

In Fig. 1, the numeral 5 indicates the bed plate of a verifying machine over which a card 6 is moved, column by column, by the usual escapement including the pivoted bail 7 which is common to the operating levers 8 actuated by the various keys 9 of the machine.

Standards 10 extend upwardly from the bed plate 5 and are connected by upper and lower stationary cross bars 11 and 12 which constitute guides for the vertically movable verifying devices embodying the features of the present invention, there being one of such devices, generally indicated at 13, associated with each of the levers 8. The upper ends of the standards 10 support a plate 14 having a housing 15 in which the various spring controlled fulcrum pins 16, one for each lever 8, are mounted. The lower end of each pin 16 engages its lever to provide a fulcrum therefor when the key 9 is pressed downwardly and if the verifying device depressed by lever 8 senses a perforation in the card 6, the pin 16 continues to act as the fulcrum for said lever and the latter will be depressed sufficiently to operate the bail 7 so that the escapement mechanism will move the card 6 to the next column to be verified upon release of the depressed key 9.

However, if the usual sensing pin encounters the card, its downward motion will be arrested and the fulcrum of the lever 8 will then be transferred to the head of said pin, with the spring of the pin 16 yielding to further pressure upon the key 9. This action prevents the lever 8 from actuating the bail sufficiently to cause the escapement to be operated. The foregoing construction and operation is well understood in the

art and needs no further amplification except to add that when the customary verifying pin similar to that shown by Cleven is employed, it has been found in actual practice that whether the pin be round or rectangular in cross section, it will invariably emboss the card when striking the same, even though only a normal pressure is exerted upon the key 9, and it has been further found that excessive pressure upon the key will cause the verifying pin to punch a hole in the card.

In the form of the invention shown in Figs. 2 and 3, the verifying device 13 is so constructed that when its sensing pin 17 contacts the card 6, continued pressure upon said device by the lever 8 will have no further effect upon the pin and, as a consequence, no indentation will be made in the upper surface of the card and hence no protuberances will be formed on the under-surface thereof. To accomplish this end, the device 13, which is slidably mounted in the guides 11, 12 is formed in two sections, one being the pin 17 and the other a sleeve 18 through the bore of which the pin extends with its lower end protruding from the sleeve for passage through a perforation in the card 6 or contact with the upper surface thereof. A spring 19 coiled about the sleeve 18 is seated in the lower guide 12 and bears against an enlarged portion 20 at the upper end of said sleeve, and said spring acts to resist downward movement of the device 13 and to restore the same after pressure upon the lever 8 is released.

The bore of the sleeve 18 is enlarged at its upper end to receive the frusto-conical operating head 21 of the pin 17 which normally rests against a seat formed by the enlarged part of the bore. In the portion 20 of the sleeve 18, which moves within the upper guide 11, said sleeve is provided with three circumferentially spaced apertures 22 in each of which is disposed a restraining element 23 preferably in the form of a ball which, under control of the head 21, is urged laterally into binding engagement with the wall of the guide 11 to prevent further downward movement of the device under pressure of the lever 8 after the pin 17 has contacted the card 6, which contact is followed by a slight movement of said sleeve relative to said pin to effect the above mentioned binding engagement.

The upper end of the bore of sleeve 18 is internally screw threaded to receive a cap 24 upon which the lever 8 rests and which has seated therein a light coil spring 25 bearing upon the head 21 of pin 17 so as to restore the latter to its normal seated position when the sleeve 18 is raised by its spring 19 following the release of pressure upon said sleeve by the lever 8.

In practice, when a key 9 is struck, its lever 8 will swing about the fulcrum 16 to exert pressure upon the cap 24 and thus force the sleeve 18 and pin 17 downwardly, and if the lower end of the pin passes through a perforation in the card 6, the downward movement of the verifying device will continue until the bail 7 is actuated to release the escapement mechanism. During this downward movement, which is limited by the stroke of the key 9, the spring 19 is compressed so that it will act to restore the device upon the release of said key. However, should the pin 17 encounter the card, its downward movement will be immediately arrested by such contact, but the sleeve 18 continues to move under pressure of the lever 8 a slight distance sufficient to permit the inclined surface of the head 21 to force the

balls 23 outwardly into binding engagement with the wall of the guide 11, whereupon both the sleeve and pin are restrained against further downward movement and the fulcrum of lever 8 is transferred from the pin 17 to the cap 24 with the result that the portion of the lever 8 engaging the bail 7 will not be sufficiently depressed to fully operate said bail. Failure of the escapement to advance the card will notify the operator that an error has been made in entering data in the card and the same may then be withdrawn from the machine for correction. The arresting of pin 17 by the card and subsequent slight relative movement of the sleeve 18 resulting in the stoppage of downward movement of the device 13, relieves all pressure upon the pin during completion of the operating stroke of the key 9 and the mere contact of the pin with the card will be insufficient to leave any appreciable mark or indentation on the upper surface of the card.

What is claimed is:

1. In a verifying device for statistical card machines, an element operable for sensing perforations in a card and for engaging said card in the absence of a perforation, means to exert pressure upon said element to operate the same, a member through which said sensing element extends and having movement with said element under the influence of said pressure means and also having movement relative to said element when the latter contacts the card, a guide for said member, and means carried by said member and coacting with said guide and element upon relative movement of said member to prevent further movement of said element and member when the former contacts said card.

2. In combination, stationary guides, a verifying device movable therein toward and away from a card to be verified and including a sensing pin adapted for contact with said card and a sleeve through which said pin extends, said sleeve having movement relative to said pin after contact of the latter with a card, and means carried by said sleeve and coacting with said guide and pin upon relative movement of said sleeve to prevent any further movement of said pin toward said card after contact therewith.

3. In combination, a stationary guide, a verifying device movable therein in the direction of a card and including a pin adapted for contact with said card and having an operating head, a member forming a support for said pin and having limited movement relative thereto after contact of said pin with a card, means to exert pressure upon said member to move the same and said pin in the direction of said card, and means controlled by said operating head and effective upon relative movement of said supporting member to engage said guide and thereby prevent further movement of said member and pin in the direction of said card.

4. In combination, a stationary guide, a verifying device movable therein in the direction of a card and including a pin adapted for contact with said card and having a conical head, a member through which said pin extends and having limited relative movement with respect thereto after said pin engages a card, means to exert pressure upon said member to move the same and said pin in the direction of said card, and locking elements carried by said member and actuated by said conical head to engage and bind against said guide to thereby limit said relative movement

and prevent further movement of said device in
said guide after contact of said pin with said card.
